UNITED STATES PATENT OFFICE

GEORGE V. GAVAZA, OF QUINCY, MASSACHUSETTS

CUSHION

Application filed January 8, 1929. Serial No. 331,062.

The present invention relates to cushions, and more particularly to cushions which are used to cushion machines or articles mounted on legs, casters or feet.

5 In many households, machines driven by motors are used in sewing, in washing clothes and dishes, in refrigeration and in spraying oil in furnaces. An annoying feature of these machines is the noise they make in operation.

10 This noise is due principally, to the transmission of the vibrations of the machines to the surfaces upon which the machines are supported. To absorb the vibrations of motor-driven household machines and thus render them noiseless it has been proposed heretofore to cushion the machines with a body formed of elastic material having a pocket in its top face in which the leg or caster of the machine is supported and having in its bottom face both an annular recess for causing the cushion to grip a supporting surface and a central air-pocket for absorbing the vibrations of the machine. Some of the motor-driven household machines are heavy and 25 their vibrations are intense. In consequence the cushion is subjected to a pulsating load. When the load surges downwardly the material over the central air pocket is distorted thus decreasing the volume of air therein and forcing some of the air out of the pocket into the annular recess. When the load surges upwardly again this air is trapped in the annular recess thus increasing the pressure therein. This transfer and trapping of 30 air is repeated as the load pulsates until the pressure in the annular recess is great enough to raise the external wall adjacent the annular recess from contact with the supporting surface and the air is dissipated. When 35 this occurs the central air pocket is flattened so that the vibrations of the machine are transmitted directly to the supporting surface.

The object of the present invention is to 40 provide a cushion for motor-driven household machines which will absorb effectively their vibrations.

To the accomplishment of this object, and 45 such others as may hereinafter appear, the various features of the present invention re-

late to certain devices, combinations and arrangements of parts as fully set forth hereinafter, the advantages of which will be readily understood by those skilled in the art.

The various features of the present invention will be readily understood from an inspection of the accompanying drawings illustrating the best form of the invention at present known to the inventor, in which,

55 Figure 1 is a view in perspective of the cushion;

Fig. 2 is a view in bottom plan, and

Fig. 3 is a view in central sectional elevation on the line 3—3, Fig. 2.

Referring to the drawings the cushion comprises a frusto-conical body 4, of elastic material such as rubber or a compound thereof having a small base 5 and a larger base 6. On the base 5 a pocket 7 is formed which is separated from the conical surface of the body by an annular wall 8. The pocket 7 receives therein the leg, foot or caster of the motor-driven household machine. The larger base 6 is provided with an annular recess 9 for causing the cushion to grip a supporting surface. The recess 9 is separated from the conical surface of the body 4 by an annular wall 10. Centrally located on the larger base 6 is an air pocket 11 which is separated from the annular recess 9 by an annular wall 12. The wall 12 is provided with three openings 13 therethrough.

80 In use the material of the cushion between the pocket 7 and air-pocket 11 yields under the vibrations of the supported machine, thus compressing the air in the air-pocket 11, the recess 9 and the intercommunicating passages 13. The compressed air absorbs the vibrations of the machine and prevents the transmission of the vibrations to the surface upon 85 which the larger base 6 rests. Because of the passages 13 between the annular recess 9 and the air pocket 11 a pressure is not built up in the recess 9 but the air surges back and forth, under the influence of the pulsating load, between the recess 9 and the pocket 11 and the pressure in the recess 9 is never great 90 enough to raise the wall 10 from contact with the supporting surface. With this construction the wall 12 provides an additional sup-

port for the load thus preventing undue distortion. This provision for increasing the volume of air subjected to compression prevents the air from attaining as high a compression as the air attains when confined within the air-pocket alone. With the present construction the vibrations of heavy machines are absorbed without distorting the inner wall 12. Consequently the vibrations are absorbed without dissipating the air in the recess 9, pocket 10 and passages 13.

The cushion is made frusto-conical, preferably, to avoid top-heaviness in the cushion and to enable the annular recess 9 to grip a large area of the supporting surface.

While the invention has been described as being particularly useful in supporting motor-driven household machines it will be apparent to those skilled in the art that the cushion may be used in supporting other household articles such for instance as musical instruments and battery-chargers to improve the tone in the case of the musical instruments and to obviate the noise in the case of battery-chargers. The cushions are useful particularly in supporting radio sets as they act as floor levelers and eliminate tube vibration and distortion caused by passing traffic or by walking and dancing in the building where the set is located.

What is claimed as new, is:

1. A cushion for motor-driven household machines, radio sets and musical instruments comprising a body formed of elastic material having a pocket in its top face in which the leg or caster of the machine is supported and having in its bottom face an annular recess for causing the cushion to grip a supporting surface and a central air-pocket communicating with the recess for absorbing the vibrations of the machine.

2. A cushion for motor-driven household machines, radio sets and musical instruments comprising a frusto-conical body formed of elastic material having a pocket in its smaller base in which the leg or caster of the machine is supported and having in its larger base an annular recess for causing the cushion to grip a supporting surface and a central air-pocket communicating with the recess for absorbing the vibrations of the machine.

3. A cushion for motor-driven household machines, radio sets and musical instruments comprising a body formed of elastic material having a pocket in its top face in which the leg or caster of the machine is supported and having in its bottom face two annular concentric walls, the inner wall having openings therethrough, said walls being separated by a recess, and an air-pocket formed within the inner wall.

In testimony whereof I have signed my name to this specification.
